Fig. 19.

FIG. 1 is a front perspective view of the bicycle stand showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left end elevational view thereof, it being understood that the right end is a mirror image thereof;

FIG. 7 is a front perspective view of our bicycle stand showing a second embodiment of our new design;

FIG. 8 is a top plan view of FIG. 7;

FIG. 9 is a bottom plan view of FIG. 7;

FIG. 10 is a front elevational view of FIG. 7;

FIG. 11 is a rear elevational view of FIG. 7;

FIG. 12 is a right end elevational view of FIG. 7, it being understood that the left end is a mirror image thereof;

FIG. 13 is a front perspective view of our bicycle stand showing a second embodiment of our new design;

FIG. 14 is a top plan view of FIG. 13;

FIG. 15 is a bottom plan view of FIG. 13;

FIG. 16 is a rear elevational view of FIG. 13;

FIG. 17 is a front elevational view of FIG. 13;

FIG. 18 is a right end elevational view of FIG. 13; and

FIG. 19 is a left end elevational view of FIG. 13.

We claim:

The ornamental design for a bicycle stand, substantially as shown and described.
